UNITED STATES PATENT OFFICE.

ROYAL M. BASSETT, OF BIRMINGHAM, CONNECTICUT.

IMPROVEMENT IN ROLLING-MILLS.

Specification forming part of Letters Patent No. 222,373, dated December 9, 1879; application filed September 4, 1879.

To all whom it may concern:

Be it known that I, ROYAL M. BASSETT, of Birmingham, in the county of New Haven and State of Connecticut, have invented a new Improvement in Rolling-Mills; and I do hereby declare the following, when taken in connection with the accompanying drawings and the letters of reference marked thereon, to be a full, clear, and exact description of the same, which said drawings constitute part of this specification, and represent, in—

Figure 1, a sectional end view of one of the heads; Fig. 2, a vertical central section of the same.

This invention relates to an improvement in the method of adjusting rolls of rolling-mills.

Heretofore the bearings have been adjusted by means of a wedge moved by a screw and working upon a correspondingly-inclined surface, so that by moving the wedge out or in the bearing would be correspondingly lowered or raised; but in such construction, in order that the bearing might be quickly raised or lowered, the principal movement has been made by a screw, and then the finer adjustment by the wedge.

The object of this invention is to use a wedge for both adjustments, one of a greater incline than the other, and so that the principal adjustment may be made by the greater incline, and the finer by the lesser incline, and in such arrangement the invention consists.

A represents one of the ends of the frame of a common rolling-mill, B representing the bearing for the unadjustable roll, and C the bearing for the adjustable roll. This is guided so as to be free to be moved up or down, as occasion may require.

Underneath the adjustable bearing C a sliding block, D, is arranged with its upper surface inclined, and the lower surface of the bearing-block C correspondingly inclined, as seen in Fig. 2. Below this sliding block D is a block, E, arranged in the frame so as to be moved vertically only.

In the upper surface of the block E is a semicircular cavity arranged to receive a sleeve, F, so supported that it may be revolved freely therein. The block E is recessed in the center, as at a; and the sleeve F has a raised screw-thread, in extent equal to the

length of the recess a, so that it will be held against longitudinal movement while free to revolve.

The under side of the inclined block D is threaded corresponding to the screw-thread on the sleeve; hence rotation imparted to the sleeve F will force the block D to move to the right or left, accordingly as the sleeve is turned, and such movement will advance or retreat the sliding block beneath the bearing C, and correspondingly cause it to rise or fall.

Through the sleeve F a shaft, H, is arranged, free to rotate, and also free for slight longitudinal movement; and on this shaft is one part, I, of a clutch fitted to engage a corresponding part, K, on the sleeve, as seen in Fig. 2, so that when engaged the rotation of the shaft will be imparted to the sleeve D.

The incline between the two parts C D is made greater than can be conveniently used for fine adjustment, and is intended only to impart a greater extent of movement.

For the finer adjustment, an inclined slide, L, is arranged beneath the vertically-movable block E, the lower surface of which is inclined to correspond to the slide L; and through the head N on the slide L a screw, P, is arranged, so that by turning the said screw the slide L will be correspondingly moved in or out, according to the direction of the screw, and correspondingly raise or lower the block E.

The incline of the slide L is comparatively slight, so that its movement causes the block E to rise or fall but slightly compared to the movement of the slide, and so that by moving the slide L a very fine adjustment may be attained.

The object of making the sleeve F tubular and the shaft through it is that, in case of wear, it is easily removed from the shaft and replaced by another.

I am aware that the inclined slide L and its adjusting-screw are not new, and therefore do not broadly claim such device; but

What I do claim is—

1. In a rolling-mill, the combination of the movable bearings with an inclined sliding block beneath it, and screw for moving said sliding block, and a second inclined slide below the first sliding block and screw to adjust it, the incline of one being greater than the

other, substantially as and for the purpose described.

2. In a rolling mill, the combination of the movable bearing with an inclined slide beneath and a screw-threaded sleeve arranged to work in a corresponding thread of the said inclined slide, and without longitudinal movement, and a shaft through said sleeve free for

both longitudinal and rotative movement with a clutch on said shaft to engage said sleeve, substantially as described.

ROYAL M. BASSETT.
